FIG. 4

FIG. 3

FIG. 2

INVENTOR.

JOHN J. WEITHAUS.

BY

Ed. B. Johnson

ATTORNEY.

UNITED STATES PATENT OFFICE.

JOHN J. WEITHAUS, OF NORTH VERNON, INDIANA, ASSIGNOR OF ONE-HALF TO
MICHAEL C. AINSBERRY, OF RUSHVILLE, INDIANA.

OIL-VAPORIZER.

1,384,004.

Specification of Letters Patent. Patented July 5, 1921.

Application filed May 3, 1919. Serial No. 294,438.

To all whom it may concern:

Be it known that I, JOHN J. WEITHAUS, a citizen of the United States, residing at North Vernon, in the county of Jennings 5 and State of Indiana, have invented certain new and useful Improvements in Oil-Vaporizers, of which the following is a specification.

My said invention consists in certain improvements in the details of construction and arrangement of parts of an apparatus for producing vapor and gas from oil and conveying it to the point of use, whereby such an apparatus is provided by which oil 10 may be converted into vapor and combustible gas hereinafter called gas, in a very inexpensive and convenient manner, and individual or small plants for such purpose provided where gas is ordinarily not available, 15 all as will be hereinafter more fully described and claimed.

Referring to the accompanying drawings which are made a part hereof and on which similar reference characters indicate similar parts,

Figure 1 is a diagrammatic view of a plant built and arranged in accordance with my said invention, and

Figs. 2, 3 and 4 detail views illustrating 30 the construction of separate parts on an enlarged scale.

In said drawings the portions marked A represent the tank for containing the oil supply, B an oil supply pipe, C an air supply pipe 35 and D a steam supply pipe. The arrangement of the parts, as well as the connections, will be better understood by a description of the operation.

The oil comes into tank A from an oil 40 supply with which the supply pipe B is connected through pipe 10, the tank being filled to any level desired, preferably a level substantially as shown in Fig. 1 and the supply controlled by means of the valves 11 and 12. 45 When the tank has been filled to the level desired, valve 11 is closed and the oil is then forced by a pump 13 through a heating coil composed of sections 14 and 15, and a terminal section 16. Said pump is connected by 50 a pipe 17 with a T-coupling 18 which joins the end of said pipe with the pipe 10 and

the supply pipe B. Another pipe 19 leads from said pump 13 to a connection with the first section 14 of the heating coil. A valve 20 is interposed in said pipe 19 for controlling the supply of oil. The air supply pipe C preferably leads from an air compressor (not shown) and is connected by a coupling member 21 to a vertical section 22 of the pipe leading to the heating coil. A valve 23 55 is provided in said compressed air pipe C for controlling the supply of compressed air.

The steam supply pipe D leads centrally through the sections of the heating coil discharging at end 24, the flow of steam being controlled by a valve 25. It will be understood, of course, that the sections of the heating coil may be as many in number as required for any particular plant, the number shown being only for the purpose of illustrating the arrangement.

Oil and air come together in the coupling member 21 in such proportions as may be regulated by means of the valves 20 and 23 65 and pass under pressure through the heating coil. The annular chamber in the heating coil surrounding the steam pipe is preferably partially filled with a spiral member like a spiral spring or wire 26, which 70 surrounds said pipe and serves to interrupt, or retard, the passage of the air and oil through the chamber and cause its intimate mixture while at the same time the heat generated by the steam causes its evaporation 75 and conversion into gas. The spring or spiral member 26 also serves to break up, agitate and mix the component elements passing through the chamber and facilitates the conversion thereof into combustible gas. 80

The gas passes through the final leg 16 of the coil, which has a Y-coupling member 27 at its upper end, to one branch of which a pipe 28 is connected and to the other branch of which a pipe 29 is connected. The pipe 28 95 connects with a dome 30 on one side of the tank A above the normal level of the oil therein and has a valve 31 by which the flow of gas thereto is controlled. The pipe 29 is connected by a pipe 32 to a dome 33 on the 100 opposite side of tank A and has a valve 34 by which it is controlled. A check valve 35

is provided in pipe 28 between valve 31 and the dome 30 and a similar check valve 36 is provided in pipe 32 between valve 34 and the dome 33. These check valves serve to prevent any backward flow from the tank A through said pipes.

The accumulated gas coming into the upper portion of tank A under pressure, as before explained, passes through domes 37 into pipe 38 and thence through pipe 39 to a service pipe 40 which leads to the burners or other points where the gas is to be utilized, or a general service pipe may be supplied by said pipe 40. A pipe 41 is connected with the pipe 28 and is provided with a valve 42 by which it may be controlled. The mixture containing combustible vapors principally coming from pipe 28 may be admitted through pipe 41 to the pipe 40 when desired.

An air supply pipe 43 leading from any source of air supply has several branches leading into the tank A. Branch 44 leads through dome 30 with its lower end near the upper surface of the normal level of the oil, and is intended to supply air to aid in cooling and vaporizing the fuel oil. Branches 45 and 46 lead to near the bottom of the tank and are intended to assist the pump in pumping the fluid oil and to act as a safety medium by aiding in lowering the oil temperature. The branch 47 leads into the upper portion of the tank in the gas chamber and is intended to supply air to cool the gas and mix therewith.

Another service supply pipe 48 leads from a connection 49 on pipe 39 to any point where it may be desired to convey the gas directly. A valve 50 is provided for controlling the same.

The valves 51 and 52 in pipe 39, valve 53 in pipe 43, valve 54 in pipe 44, valve 55 in pipe 45, valve 56 in pipe 46 and valve 57 in pipe 47 are all provided for controlling the flow through said pipes as may be required by a proper operation of the apparatus.

A gage 58 is provided on the side of the tank A at its lower end to indicate the level of the oil. A gage 59 is provided on its side near its upper end to indicate the gas pressure therein. A gage 60 is provided in pipe 29 between the Y 27 and the valve 52 to indicate the pressure of the combined gas and oil therein, and check valves provided in the lines wherever required to guard against back flow or blowouts.

When the oil in the tank is at the point where an additional supply is needed the valve 20 is closed and valves 11 and 12 are opened to permit the oil to flow from the main supply tank into said tank A. In case it is desired to heat the oil before it is put into the tank A valves 12 and 23 are closed and valves 11 and 20 opened and the oil is pumped through the heating coil and

through pipes 28 and 32 through domes 30 and 33 into the tank. By this means the oil may be brought to a high temperature before it is mixed with the air and converted into gas by the operation heretofore described. The valves are, of course, in all instances properly adjusted to give the required mixture and to control the flow of the several elements in the direction desired.

As indicated in Fig. 3 the coils inserted in the final member 16 of the heating coil extend into the branches of the Y and serve to break up the mixture and keep the elements thoroughly intermingled as they are discharged into the pipes 28 and 29. A similar spiral wire 61 is mounted in pipe 62 adjacent to the burners 63 for a similar purpose.

Having thus fully described my said invention, what I claim as new and desire to secure by Letters Patent, is:

1. In an oil vaporizing apparatus, the combination of a tank, a heating coil, a source of oil supply leading to the tank, a pipe leading from the tank to the heating coil, an air supply connecting with the oil supply at a point adjacent to its connection with the heating coil, pipes leading from the heating coil back to the tank at points above the normal oil level therein, a service pipe connected with the upper portion of said tank, air supply pipes connected with said tank, and a pump for forcing the oil and air under pressure through the heating coil and into the tank, substantially as set forth.

2. In an oil vaporizer, the combination of a tank and oil supply, a connection from the oil supply to said tank, a heating coil, a connection from the tank to the heating coil, a pump interposed in said connection, a connection leading to an air compressor also joined to said connection leading to the heating coil, branch pipes leading from said heating coil to opposite sides of the tank above the oil level therein, domes on the top of tank, a service pipe to connect with said domes, and air supply pipes connecting with said tank, substantially as set forth.

3. In an oil vaporizer, the combination of a tank, an oil supply leading into said tank, a heating coil comprising steam pipes passing through coils of larger pipes, spiral members surrounding said steam pipes in said larger pipes, connections from said heating coil leading back to the upper end of the tank, a connection with the upper end of the tank to a service pipe, and valves for controlling the flow of the oil, gas and air through the several parts of the apparatus, substantially as set forth.

4. In an oil vaporizer, the combination of an oil tank, a heater, a connection from the oil tank to the heater, means for forcing oil and air through said heater under pressure, wire spiral members mounted in said heater

for breaking up and mixing the oil and air, my hand and seal at Indianapolis, Indiana,
pipes leading from said heater back to the this 17th day of April, A. D. nineteen hun-
upper portion of the tank, a service pipe dred and nineteen.
connected with the upper portion of said JOHN J. WEITHAUS. [L. s.]
5 tank, and valves for controlling said several Witnesses:
parts, substantially as set forth.

In witness whereof, I have hereunto set

E. W. BRADFORD,
M. L. SHULER.
